UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS.

SEALING-STRIP MACHINE.

1,187,030.

Specification of Letters Patent. Patented June 13, 1916.

Application filed February 12, 1912. Serial No. 677,208.

To all whom it may concern:

Be it known that I, JOHN BERG, a citizen of the United States, residing at Chicago, in the county of Cook and State of Illinois, 5 have invented a new and useful Improvement in Sealing-Strip Machines, of which the following is a specification.

My invention relates particularly to machines adapted to hold a roll or rolls of sealing-strip material and provided with means for moistening the gummed surface of the sealing strip and with means for severing the sealing strip.

My primary object is to provide a machine of simple construction and improved operation.

The invention is illustrated in its preferred embodiment in the accompanying drawing, in which—

20 Figure 1 represents a vertical sectional view of a machine embodying my invention; Fig. 2, a horizontal sectional view of the same; Fig. 3, a broken front view of the removable cover employed, showing it equipped at its front portion with resilient fingers, with a strip-severing knife, and with a strip-positioning device located beneath said knife; and Fig. 4, a broken transverse vertical section taken, as indicated, at line 25 4 of Fig. 1.

In the preferred embodiment of my invention the machine comprises a roll-holder A; a moistening device B; a strip-severing device C; and a paper-positioning device E.

35 The base-portion of the roll-holder and the well 2 of the moistening device are preferably cast integrally with each other. In the well 2 is journaled a roll 3. The roll-holder A is preferably in the form of a casing, which has sides 4 and a back 5 securely mounted on the case 1. The upper edge of the back 5 is designated 6; the side-plates 4 rise above the back 6 and have their upper ends curved, or approximately semi-circular, 40 as indicated at 7. The sides 4 and back 5 may be conveniently formed, integrally with each other, of sheet metal. The curved cover 8, which is preferably formed of resilient sheet metal, forms a casing-top, the lateral edges of the member 8 being beaded, as indicated at 9, to bear upon the curved upper edges of the side plates 4 of the casing. At its rear end the cover 8 is provided with an outwardly struck centrally disposed tongue 45 or locking member 10 adapted to pass

through a loop 11 disposed at the outer side of the upper portion of the back-plate 5. The loop 11 may be formed by severing the metal partially and striking it outwardly, as indicated in Fig. 1. The tongue 10 is provided near its extremity with a catch 12 adapted to lockingly engage the web of the loop 11. The cover 8 is equipped centrally at its front end with an inwardly and upwardly curved hook 13 which engages a cross-bar 14 which connects the front portions of the side-members of the casing. Above the rod 14 and on the outer surface of the front portion of the cover 8 is secured the strip-severing device C. This comprises 70 a curved sheet-metal member having its upper portion fixedly secured to the cover 8, as by means of rivets 15. The member C projects in front of the casing, and has a severing or tearing edge 16 which is presented 75 downwardly and preferably somewhat forwardly. The hook 13 is preferably formed by severing a portion of the metal of the cover on three sides and curving the severed portion inwardly, as will be readily understood from Figs. 1 and 3.

The paper positioning device E is carried by the cover 8, being disposed beneath the severing-device C, and preferably comprises 80 a sheet-metal member which normally projects substantially horizontally in front of the portion of the cover 8 to which it is pivotally connected. The pivotal connection between the member E and the cover is effected by means of lugs 17 carried by the 85 corners of the member E, said lugs passing freely through perforations 18 in the cover and being bent toward each other. Thus, the lugs 17 are adapted to afford stops which limit the downward swing of the member E. 90 The connections are such, however, as to permit the member E to swing upwardly freely when the gummed strip 19 is drawn upwardly to perform the severing operation. The strip 19 extends from the roll 20 which 95 is contained in the holder or casing A.

In the casting operation, the base-portion 1 of the receptacle A is formed with straight longitudinal side-members 21 forming part of a base-rim 22 which extends entirely 100 around the base of the machine and is adapted to rest upon a counter or table; and between the side-members 21 of the base, the bottom-wall curves upwardly, as indicated at 23 and 24, thus providing a round- 110

ed surface or concavity, in which the bottom of the roll 20 rests. At the front portion of the machine the curved bottom joins the upper edge of the rear portion of the well 2, 5 thus providing a throat-portion, as indicated at 25, over which the sealing-strip may be drawn. The curved bottom, at its rear, is joined to the upper end of a rear flange 26 which rises from the base-rim 22. The 10 rear plate 5 of the casing embraces the flange 26, and the side-plates 4 embrace the lateral edges of the curved bottom, the base-rim 22 being suitably recessed or journaled to receive the lower edges of said rear plate 15 and said side-plates. The curved walls of the bottom are provided with suitably spaced slots 27 adapted to receive the lower ends of adjustable and removable partitions or plates 28. The plates 28 may be tin plates and as 20 many of said plates may be employed as may be desired, to divide the chamber A into as many compartments as may be necessary to accommodate the number of rolls of sealing-strips to be placed in the machine. 25 Obviously, the width of the compartments may be regulated to suit the widths of roll used, as many of the adjustable partitions being employed as may be necessary, and said partitions positioned according to requirements. For convenience of illustration, 30 only one roll 20 has been shown in the machine.

It is desirable to apply friction to the sealing-strips, both for the purpose of preventing the rolls from unwinding unduly and for the purpose of preventing movement of the sealing-strip during the severing operation. The preferred manner of making provision for this purpose is to equip the lower front end of the cover 8 with resilient fingers or springs 29 which are separated by slots 30. The fingers 29 are adapted to bear on the inner surface of the front portion 24 of the curved bottom wall of the casing, the 40 extremities of the fingers being curved upwardly, or away from the wall 24, as indicated at 31. The sealing-strips are adapted to pass between the resilient fingers 29 and the wall 24. The spacing of the slots 30 corresponds with the spacing of the slots 27 in the curved bottom walls of the casing, so that the partition plates 28 will pass freely through the slots 30. By reason of the curvature of the walls 23 and 24, it will be understood that ample bearing surface is provided to maintain the partition plates 28 in upright position, so that the rolls will be kept separated from each other and maintained in upright position; and this will be 50 true regardless of the number of rolls employed.

In the use of the improved device, the rolls are inserted in the machine before the cover 8 is applied, the end-portions of the 55 sealing-strips being drawn out over the

throat-portion 25. The cover is then applied by inserting the resilient fingers 29 between the transverse rod 14 and the throat-portion 25 and bringing the hook 13 into engagement with the rod 14, after which the cover 70 is pressed down on to the curved upper edges of the side-plates 4 and the tongue 10 entered in the loop 11, where the catch 12 engages the loop and securely holds the cover in place. In this operation, the cover 75 is placed under flexure, so that the catch 12 will be maintained in engagement with the loop. It is observed that the loop affords sufficient space to permit the tongue 10 to be pressed inwardly to disengage the catch 80 when it is desired to effect removal of the cover.

The paper-positioning device E normally holds the projecting end of the sealing-strips away from the severing device 16, the strips being normally bent over the throat-portion 25, as shown in Fig. 1. The operator grasps the end-portion of the strip, draws the strip over the roll 3, which is partially immersed in water, until a sufficient length of the strip 90 has been moistened, then swings the strip upwardly and severs it on the device 16. In this operation, the device E is swung upwardly; and after the severing operation the device E swings downwardly 95 by gravity till its movement is limited by the stops 17. This throws the extremity of the sealing strip away from the severing edge of the device 16 and causes the end-portion of the strip to project beyond the device E, where it can be readily grasped in the next operation. The devices C and E are so positioned with relation to the moistening roll 3 that when the strip is severed, the severing will be effected just in 100 the rear of the moistened portion of the strip, so that a dry portion of the strip will be presented for the next operation. Thus, it will be unnecessary for the operator to touch the moistened portion of the mucilage 110 or adhesive. It is understood, of course, that gummed strips of paper or other flexible material are now quite commonly employed for sealing packages; and the improved machine is well adapted to the purpose of handling such sealing-strips, enabling the work of applying the sealing-strips to packages to be rapidly performed in a cleanly manner. Moreover, the improved machine can be constructed at a 115 very moderate cost, is readily manipulated and possesses the many points of advantage indicated above.

It may be added that the machine is likewise adapted to handle strips of gummed labels, internal revenue stamps, etc. It is noteworthy that each strip of gummed tape 125 will have one or more resilient fingers bearing on it, according to the width of the tape; and the thickness of one strip will in no 130

wise affect the tension on another strip. Hence, different thicknesses of tape may be used, without affecting the operation.

The foregoing detailed description has 5 been given for clearness of understanding only and no undue limitation should be understood therefrom, but the appended claims should be construed as broadly as permissible in view of the prior art.

10 What I regard as new, and desire to secure by Letters Patent, is—

15 1. A machine of the character set forth, comprising a roll-holder having at its front portion a concave bottom-wall, a well joined to said bottom-wall, and affording a throat-portion over which the sealing-strip may be drawn, a moistening roll mounted in said well, a severing device disposed above said well, and a spring finger conforming to and 20 bearing on the bottom-wall in the rear of said throat-portion.

25 2. A machine of the character set forth, comprising a roll-holder having a curved bottom-wall, a well in front thereof with which said bottom-wall forms a junction affording a throat-portion, a cover member equipped with a resilient finger bearing on said curved bottom wall, and a severing device disposed above said well.

30 3. A machine of the character set forth, comprising a casing having at its front portion a bottom-wall, a well in front thereof forming a junction with said wall and affording a throat portion over which a sealing strip may pass, a cover member having a series of resilient fingers bearing on said bottom wall, a severing device carried by said cover-member and disposed above said throat-portion, and a strip-positioning member 35 movably mounted on said cover-member and disposed between said severing-device and said throat-portion.

40 4. A machine of the character set forth, comprising a roll-holding receptacle, a moistening device, and a removable cover 45 for said receptacle equipped at its front portion with a severing-device and equipped below said severing device with an independent, movably mounted forwardly-projecting strip-positioning member.

45 5. A machine of the character set forth, comprising a roll-receptacle having a cross-member at its front portion, said receptacle having a bottom-wall at its front portion, a moistening device in front thereof, a cover 55 equipped at its front portion with a hook engaging said cross-member and equipped below said hook with a resilient member engaging said bottom wall, a strip-severing 60 device, and means for securing the rear portion of the cover to the receptacle.

6. A machine of the character set forth,

comprising a roll-receptacle having a rear wall and side walls projecting above the rear wall and having curved upper edges, a cross-member joining the front portion of said side-walls, said receptacle having a curved bottom wall below said cross-member, a well in front of said curved bottom-wall and forming a junction therewith affording a 65 throat-portion, and a resilient cover-member having a hook engaging said cross-member and equipped below said hook with resilient fingers engaging said curved bottom-wall, said cover-member bearing upon the upper 70 edges of said side-walls and equipped at its rear end with a catch-device, disengageably connected with the rear wall of said receptacle, and a severing-device carried by the front portion of said cover-member. 80

7. A machine of the character set forth, comprising a roll-receptacle having a rear wall and side walls projecting above the rear wall and having curved upper edges, a cross-member joining the front portion of 85 said side walls, said receptacle having a curved bottom wall below said cross-member, a well in front of said curved bottom-wall and forming a junction therewith affording a throat-portion, and a resilient 90 cover-member having a hook engaging said cross-member and equipped below said hook with resilient fingers engaging said curved bottom-wall, said cover-member bearing upon the upper edges of said side-walls, and 95 equipped at its rear end with a catch-device, disengageably connected with the rear wall of said receptacle, and strip-severing and strip-positioning devices mounted on the front portion of said cover-member. 100

8. A machine of the character set forth, comprising a roll-receptacle equipped at its front portion with a cross-member, a moistening device in front thereof, a curved cover-member equipped at its front portion 105 with a hook engaging said cross-member, a loop carried by the rear wall of the receptacle, and a catch-equipped tongue carried by the rear portion of said cover-member and engaging said loop. 110

9. A machine of the character set forth, comprising a receptacle having curved bottom walls provided with a series of slots, a moistening device disposed in front thereof, a cover-member equipped with a series of resilient fingers separated by spaces corresponding with said slots, partition members extending through said slots, and a severing device mounted on said cover-member above said moistening device. 115

JOHN BERG.

In presence of:—

L. HEISLER,

R. W. RAYMOND.
